US0D1073445S

(12) **United States Design Patent** (10) **Patent No.:** **US D1,073,445 S**
(45) **Date of Patent:** **** May 6, 2025**

(54) **CONNECTOR FOR CANOPY**

(71) Applicant: **Wuyi Shenhua Industry & Trade Co., Ltd.**, Jinhua (CN)

(72) Inventors: **Heng Xu**, Jinhua (CN); **Zhuonan Zhu**, Jinhua (CN)

(73) Assignee: **Wuyi Shenhua Industry & Trade Co., Ltd.**, Jinhua (CN)

(**) Term: **15 Years**

(21) Appl. No.: **29/823,830**

(22) Filed: **Jan. 20, 2022**

(51) LOC (15) Cl. **21-04**

(52) U.S. Cl.

USPC **D21/839**; D8/354

(57) **CLAIM**

The ornamental design for a connector for canopy, as shown and described.

DESCRIPTION

FIG. 1 is a top perspective view of a connector for canopy showing our new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings illustrate the portions of the connector for canopy which form no part of the claimed design.

1 Claim, 8 Drawing Sheets
